BLAST FURNACE BIN

Arthur J. Boynton, Winnetka, and Harold K. Smith, Chicago, Ill., assignors to H. A. Bras-sert & Company, Chicago, Ill., a corporation of Illinois

Application August 28, 1939, Serial No. 292,210

3 Claims. (Cl. 209—257)

This invention relates to new and improved material handling apparatus, and more particularly to apparatus adapted both to separate material into different sizes and to selectively deliver it as required.

While the invention may be used for other purposes, it is particularly applicable to the handling of material for charging blast furnaces or the like. It is often desirable for metallurgical reasons related to the operation of the furnace, to separate fine material from coarse material in order to charge them separately into the furnace. The present invention may be carried out by using the ordinary bins and lorry car or scale car in the customary manner. With previously used apparatus and methods, such separation of the charge into different sizes has required an extra handling of the material through a screening station.

It is an object of the present invention to provide apparatus for delivering material from storage means to a movable receptacle or conveyor, said apparatus also serving to separate the material according to size.

It is a further object to provide means of this character with which the separated material may be selectively discharged into the movable receptacle.

It is also an object to provide means whereby the same driving mechanism serves to cause both the separating action and the selective delivery of the separated material.

It is an additional object to provide a construction in which the driving mechanism may be carried upon the movable receptacle, such as a lorry or scale car, and may be operatively connected to different delivery apparatus as desired.

Other and further objects will appear as the description proceeds.

We have shown one form of apparatus according to the present invention somewhat diagrammatically in the single figure of the accompanying drawing.

The bin 11 is provided with a lower opening 12 adapted to discharge material from the bin into a tray 13. This tray 13 is hung from the bin structure by hangers 14 and 15, which are provided with cushioning means 16 and 17. The main portion of the bottom of the tray 13 is solidly closed, but an intermediate portion 18 is formed with openings or perforations to permit material smaller in size than the openings to fall into the lower tray 19. The tray 13 has the cross bar 20 secured thereto adjacent the dis-

charge end to serve as a connecting means for the vibrator 21.

The tray 19 is suspended below tray 13 by the links 22 and 23. The tray 19 has a closed bottom and, at its right or delivery end as seen in the drawing, is provided with a swinging gate 24 hung on the pivot 25. A stop 26 limits inward swinging movement of the upper portion of the gate. The gate 24 is provided with the lugs 27 carrying the cross bar 28 for operating the door 10 and vibrating the tray.

The lorry or scale car 29 is shown as traveling on tracks 30, so that it may be brought into receiving position below the trays 13 and 21. The vibrator 21 is supported upon the scale car 29 by the framework 31, from which it is suspended by hanger 32 having cushioning means 33. The rear adjusting cylinder 34 is connected to the vibrator 21 by rod 35. The forward lifting cylinder 36 is connected to the actuating arm 37 of the vibrator by the rod 38. The actuating arm 37 is provided with the downwardly opening forked portion 39 adapted to selectively engage either the bar 20 of tray 13 or the cross bar 28 of the lower tray 19.

The vibrator 21 may be of any standard construction and since its details of construction form no part of the present invention, they need not be described. It is a power operated apparatus adapted to effectively vibrate any material supporting tray or conveyor to which it may be connected to cause material to flow over and discharge from the vibrated material support. It will be apparent that, by operation of the cylinders 34 and 36, the vibrator may be brought into operative connection with the tray 13, as shown in full lines in the drawing, or into connection with the lower tray 19, as shown in broken lines. When the forked portion 39 of the vibrator actuating arm 37 engages the cross bar 28 on the gate 24 of the lower tray, the vibrator is moved to the left by the adjusting cylinder 34 to open the gate against the stop 26. The vibrator is then put in operation and vibrates the tray 19 to deliver material therefrom into the car 29, while also serving to hold the gate 24 open.

It will be apparent from the above description, taken in connection with the drawing, that the construction of the present invention serves to screen material during the delivery operation and to separately and selectively deliver the material to the scale car. A sufficient portion of the bottom of the tray 13 is solid so that the tray serves to seal off the storage bin against loss of material

when the tray is not vibrated. This tray acts, therefore, as a closure or gate for the bin.

Approximately horizontal transfer of material from either tray to the scale car is effected by 5 the vibration transmitted to the tray from the vibrator carried by the car. It is not necessary to provide separate vibrators for each bin or tray as the car when in position to receive material from any bin provides the power for the 10 delivery therefrom.

While one preferred form of construction has been shown, this is to be understood to be illustrative only, as the apparatus is capable of 15 change and modification to meet differing conditions and requirements. Other forms of bins and of trays may be used and other forms of apparatus for carrying away the material discharged from the trays. We contemplate, therefore, such changes and modifications as come 20 within the spirit and scope of the appended claims.

What is claimed is:

1. Material handling apparatus comprising 25 storage means for the material, a delivery tray located to receive material from the storage means, a portion of the tray being provided with openings to form a screen, a receptacle located below the screen portion of the tray, movable means adapted to receive material from the delivery tray and the lower receptacle, and vibrator mechanism having connecting means for selective connection to the tray or receptacle to vibrate either of said units to cause discharge 30 therefrom onto the movable means.

2. Material handling apparatus comprising storage means for the material, a delivery tray located to receive material from the storage means, a portion of the tray being provided with openings to form a screen, a receptacle located 5 below the screen portion of the tray, a normally closed end gate for said receptacle, movable means adapted to receive material from the delivery tray and the lower receptacle, and vibrator mechanism having connecting means for selective connection to the tray or receptacle to vibrate either of said units to cause discharge therefrom onto the movable means and to open the end gate of the receptacle when connected thereto. 10

3. Material handling apparatus comprising 15 storage bins for the material, a delivery tray located below a bin, said tray having a solid bottom portion serving as a closure for said bin and receiving material therefrom, a further portion of the tray being provided with openings to form 20 a screen, a receptacle located below the screen portion of the tray, a movable car adapted to receive material from the tray and the lower receptacle, and vibrator mechanism having connecting means for selective connection to the tray 25 or receptacle to vibrate either of said units, vibration of the tray causing material to flow over the screen portion and over the discharge end of the tray, vibration of the receptacle serving to cause material dropping into the receptacle 30 from the tray through the screen to flow over the discharge end of the receptacle.
